(57) CLAIM

We claim the ornamental design for a pet bath, as shown and described.

DESCRIPTIONFIG. 1 a perspective view of a pet bath of the new design.
FIG. 2 is a first side view of the pet bath of FIG. 1.

FIG. 3 is a second side view of the pet bath of FIG. 1.

FIG. 4 is a front elevational view of the pet bath of FIG. 1.

FIG. 5 is a back elevational view of the pet bath of FIG. 1.

FIG. 6 is a top view of the pet bath of FIG. 1; and,

FIG. 7 is a bottom view of the pet bath of FIG. 1.

The broken lines illustrate portions of the pet bath that form no part of the claimed design.
